[57] CLAIM

The ornamental design for a drawer front or similar article, substantially as shown and described.

DESCRIPTION

FIG. 1 is a front elevational view of a drawer front, illustrating the ornamental design of the invention; FIG. 2 is a front perspective view of a drawer front, illustrating the ornamental design of the invention, shown attached to a drawer (not part of the present invention) in phantom line, the drawer being abbreviated to conserve space;

FIG. 3 is a top plan view of a drawer front, illustrating the ornamental design of the invention, shown attached to a drawer (not part of the present invention) in phantom line, the drawer being abbreviated to conserve space;

FIG. 4 is a right side elevational view of a drawer front, illustrating the ornamental design of the invention, shown attached to a drawer (not part of the present invention) in phantom line, the drawer being abbreviated to conserve space;

FIG. 6 is a cross-sectional view of a drawer front, taken along line 6—6 in FIG. 1, illustrating the ornamental design of the invention;

FIG. 7 is a cross-sectional view of a drawer front, taken along line 7—7 in FIG. 1, illustrating the ornamental design of the invention; and

FIG. 8 is a front perspective view of a drawer front, illustrating an alternate embodiment of the ornamental design of the invention.

This application is related to the subject matter of co-pending and commonly assigned U.S. patent application Ser. No. 06/514,917, filed July 18, 1983, for door and drawer front having a recessed grasping surface.
